UNITED STATES PATENT OFFICE.

JOSEPH COLDWELL AND CHRISTOPHER GILES GILDARD, OF FALL RIVER,
MASSACHUSETTS.

DESIGN FOR A DROP-BAR.

SPECIFICATION forming part of Design No. 29,979, dated January 10, 1899.

Application filed November 12, 1898. Serial No. 696,308. Term of patent 14 years.

To all whom it may concern:

Be it known that we, JOSEPH COLDWELL and CHRISTOPHER GILES GILDARD, citizens of the United States, residing at Fall River, 5 in the county of Bristol and State of Massachusetts, have invented and produced a new and original Design for Drop-Bars for Electrically-Operated Stop-Motions for Looms, of which the following is a specification, reference being had to the accompanying drawings, forming part thereof.

Figure 1 is a face view or elevation of a drop-bar, showing our new design. Fig. 2 is an edge view of the same.

15 As shown in the drawings, the leading or material feature of our design consists of a drop-bar, in one end of which is formed a

longitudinal slot A', the edge of said slot near its lower end being converged to form opposite internal shoulders D, and beyond them a 20 narrow opening or slit C, the edges of the latter at points near their lower ends diverging to form an angular opening or entrance E.

Having described our invention, what we claim as new, and desire to secure by Letters 25 Patent, is—

The design for a drop-bar as herein shown and described.

JOSEPH COLDWELL.
C. GILES GILDARD.
